CLARENCE D. PLATT, OF BRIDGEPORT, CONNECTICUT.

SEALABLE FUSE-PLUG.

1,226,808.

Specification of Letters Patent.

Patented May 22, 1917.

Application filed February 29, 1916. Serial No. 81,245.

To all whom it may concern:

Be it known that I, CLARENCE D. PLATT, a citizen of the United States, residing at Bridgeport, county of Fairfield, State of Connecticut, have invented an Improvement in Sealable Fuse-Plugs, of which the following is a specification.

This invention relates to the class of fuse plugs commonly used for the protection of small branch circuits and which are so constructed that a fusible strip within the plug will either melt or blow when subjected to an excess of current and thus prevent injury to lamps or other devices on the circuit beyond the plug. The use of fuse plugs is common, they are inexpensive and can easily be obtained by anyone. As a result it is not uncommon for fuse plugs to be deliberately changed by flat rate consumers and plugs of greater carrying capacity substituted, or plugs are maliciously tampered with by unauthorized persons, resulting in the burning out of or serious injury to delicate devices or apparatus which may be in the circuit. The fuse blocks for these plugs are usually adapted to receive the plugs in pairs.

My invention therefore has for its object to provide simple and inexpensive means whereby, when the central station men have inserted the proper plugs, they may be sealed in place, so that plugs of greater carrying capacity cannot be substituted by customers for the purpose of defrauding the central station, and malicious tampering with the plugs by anyone is wholly prevented, as the plugs cannot be removed without breaking the seals.

Another object of the invention is to provide simple and convenient sealable means for preventing the theft of current in unoccupied tenements, stores, factories, &c., without removing the meter.

With these and other objects in view, I have devised the novel sealable plug which I will now describe, referring to the accompanying drawing forming a part of this specification and using reference characters to indicate the several parts:

Figure 1 is a perspective of the cap of either a fuse or dummy plug embodying my invention;

Fig. 2 a section on the line 2—2 in Fig. 1;

Fig. 3 a longitudinal section of a fuse plug embodying my invention;

Fig. 4 an elevation partly broken away of a dummy plug embodying my invention, and Fig. 5 is a plan view of a fuse block with two of my novel plugs sealed therein.

Fuse plugs as ordinarily constructed comprise a chambered body 10 of insulating material, a cap 11 covering the chamber and provided with an opening 12, a disk of transparent material, usually mica, and generally known as a mica window, closing the opening and retained in place by the cap, a contact tip 14 seated in the closed end of the body, a screw shell 15 and a fuse strip 16 which connects the contact tip with the screw shell, is confined within the chamber of the plug and is visible through the window. It will of course be understood that the special details of construction of the plug are wholly immaterial so far as the present invention is concerned. In carrying out my invention, I punch out straps from the metal of the cap, leaving both ends attached, and thus form eyes 17 to receive the wires or strips of seals. The caps are secured in place in the usual manner by closing the edges of the caps under the flanges of the bodies, as at 18, in Figs. 3 and 4. 19 denotes a fuse block of ordinary construction. The bodies of my novel sealable fuses are turned into the sockets in the fuse blocks in the usual manner, as clearly shown in Fig. 5. The seal comprises a wire or strip 20 which is passed through eyes of contiguous fuse caps. One end of the wire or strip is ordinarily molded into a seal 21 of relatively soft metal, which is provided with a hole through which the other end of the wire is passed after being passed through the eyes of two caps, the metal of the seal being then closed about the wire by a suitable punch which impresses suitable identifying marks into the seal to prevent unauthorized removal and the substitution of another seal. As the use of this class of seals is common, fuller description is not thought to be required. In fact, the special type of seal used is wholly immaterial so far as the present invention is concerned. 22 in Fig. 4 denotes a dummy fuse body provided with a cap having eyes as before, which may be used in lieu of a live fuse plug to prevent theft of current in unused buildings. Precisely the same result may be secured by using an ordinary fuse that has been burned out or blown.

In case of a fuse block having three fuse

plugs, the two outer plugs may be sealed to the central plug. It will thus be seen that by providing the caps of fuse plugs with eyes, making them sealable, I have produced a plug which will effectually prevent theft of current, and will prevent tampering with the plugs and damage to delicate apparatus from excess of current.

Having thus described my invention I 10 claim:—

1. A fuse plug of the character described comprising, in combination with a body of insulating material having an open chamber therein, a substantially transparent disk 15 closing the opening to said chamber, and a metallic cap adapted to retain said disk in place, said cap being provided with an integral bridging strap struck out from the metal of the outer face thereof, whereby an 20 eyelet is formed for the reception and retention of a sealing strand of flexible material.
2. In combination, a fuse plug, said plug comprising a body of insulating material having an open chamber therein, a substantially transparent disk closing the opening to said chamber, a metallic cap adapted to 25

retain said disk in place, said cap being provided with a bridging strap struck out from the metal of the outer face thereof whereby an eyelet is formed, a strand of flexible material passing through said eyelet and thus engaging said cap, another body through which said strand is directed to engage the same, and means for sealing the ends of said strand.

3. In combination, a plurality of fuse plugs, each plug comprising a chambered body of insulating material having an open chamber therein, a substantially transparent disk closing the opening to said chamber, 40 a metallic cap adapted to retain said disk in place, each of said caps being provided with a series of integral bridging straps struck out from the metal of the outer face thereof whereby eyelets are formed and contiguous caps may be interlaced irrespective of the rotative positions thereof, and a strand of flexible material interlacing said caps through contiguous eyelets, and means for sealing the ends of said strand.

In testimony whereof I affix my signature.
CLARENCE D. PLATT.
